UNITED STATES PATENT OFFICE.

RICHARD FORD JENKINS, OF SYDNEY, AND DAVID WALTER PRICE, OF CHATSWOOD,
NEW SOUTH WALES, AUSTRALIA.

WELL-BORING TOOL.

Application filed November 14, 1922. Serial No. 600,957.

To all whom it may concern:

Be it known that we, RICHARD FORD JENKINS and DAVID WALTER PRICE, subjects of the King of Great Britain and Ireland, and residents, respectively, of Union Street, Mosman, Sydney, in the State of New South Wales, Commonwealth of Australia, and McLean Avenue, Chatswood, in the State aforesaid, have invented certain new and useful Improvements in Well-Boring Tools (for which we have filed application in Australia No. 8470, filed 16th August, 1922), of which the following is a specification.

In rotary well-boring it is frequently necessary that some means or method should be applied to prevent material around the bore from falling in and choking the bit as well as rendering its extraction extremely difficult if not impracticable.

To prevent this it is usual to use bore-casing, but as the latter is necessarily of less internal diameter than the bore while the overall diameter of the bit is not less than the bore, it follows that the bit must be extracted before the casing is put in, and if the bore is to be continued after inserting casing a smaller bit and smaller casing must be employed for such continuation. Thus in ground which requires the support of casing the depth to which a bore of equal diameter throughout can be bored is limited.

The object of our invention is to provide an operative rotating tool which will be more efficient than any hitherto in use, and which is capable of extraction through the casing so that the latter may immediately follow the tool as the boring proceeds, it not being necessary to extract the tool before inserting the casing.

With this object our invention consists in a tool comprising a bit operating in advance and a following under-reamer constructed to expand to set dimensions when operating and to automatically contract when its weight is suspended on the bore rod. The bit is constructed and proportioned to bore a hole of less diameter than the internal diameter of the casing and to pass through the latter, while the reamer is constructed to cut an annulus about the hole formed in advance and enlarge same to the required finished diameter which is not less than that of the outside of the casing to be used.

The invention also consists in an under-reamer comprising a body which may be in-

tegral with or attached to the bit-body, a pair or more of pendant arms pivoted to said body and hanging in longitudinal recesses formed therein, said arms carrying chisel-edged cutting tools, and said arms being radially expressed during the boring operation but retracted when the weight of the tool as a whole is suspended on the boring rod.

The invention further consists in other novel features and combinations and arrangements of parts as hereinafter described with reference to the accompanying drawings and particularized in the appended claims.

As in some ground considerable depth may be bored without the use of casing, it may not be always necessary to use the under-reamer until the necessity for casing arises, and therefore the complete tool forming the subject of this invention is most conveniently formed in two mutually attachable and detachable main parts either of which may be separately attached to the bore rod, the lower end of the reamer-body being formed for the attachment thereto of the bit-body. It is to be understood however that the forming of the bit-body and reamer-body in one piece is within the scope of this invention.

The accompanying drawings illustrate an embodiment of our invention in its preferred form but we do not limit our invention to the actual construction depicted therein.

In the drawings—

Fig. 1 is an elevation partly in section showing the parts in operative position,

Fig. 2 an elevation with the arms of the reamer retracted, and

Fig. 3 a part elevation when the tool is turned 90° from the position shown in Fig. 2.

Fig. 4 is a sectional plan on line 4, 4, of Fig. 1.

Fig. 5 a sectional plan on line 5, 5, of Fig. 1, and

Fig. 6 a part sectional elevation of the bit.

The bit-body 1 is of the horizontal sectional configuration shown in Fig. 5 having one axis longer than the other, and bluntly tapered or coned at its lower end where it is through-slotted to receive a drill 2 which neatly fits in said slot, the upper end of the drill being of V shape as clearly shown at 3 in Fig. 6 so that the drill is prevented

from falling out. The bit-body includes a the bore rod, it moves downwardly on the screwed threaded nipple 4 formed to screw plunger 24 until the keys 28 contact with into a coupling 5. the upper shoulders of the recesses 27.

At each side and at each end that is on 5 each end of the shorter axis and of the longer axis, the bit-body is longitudinally grooved, and in said grooves are fitted pairs of chisel-edged cutting tools 6, 6 and 7, 7, each tool being of sufficient width to project slightly beyond the surface of the body, 10 and of sufficient length to project slightly below the lower face or shoulder of the body.

It will be observed that the edges of one 15 pair of tools 6, 6 are arranged in a plane slightly above the cutting edges of the drill 2, and that the edges of the other pair of tools 7, 7 are disposed in a plane slightly higher still. Thus the drill 2 bores a hole 8 20 (Fig. 1) the tools 6, 6 cut an annulus 9 and the tools 7, 7 an annulus 10. The hole is thus progressively enlarged to the diameter required to be bored by the bit.

The shank of each chisel-edged tool is 25 longitudinally slotted as at 11, and the outer face is recessed as at 12 about said slot to accommodate the head of a set-screw 13 which passes through the slot 11 and screws into any one of a series of threaded holes 14 30 in the body. Thus longitudinal adjustment of the tools to compensate for wear, is permitted.

The sleeve 5 into which is screwed the 35 nipple 4 of the bit-body is screwed on to a nipple 15 constituting a reduced part of the reamer body 16 which is of the sectional configuration shown in Fig. 4, and formed to freely pass through the casing to be used.

On diametrically opposite sides the body 40 is slotted as at 17 and in each slot is an arm 18 pivotally hung on a bolt 19 and formed at its other end into a head 20 carrying chisel-edge tools 21 fitted in dovetail radial slots in the head, and secured therein by 45 dovetailed plates 21¹ and set-screws 21². Secured by means of pins or setscrews 22¹, to the inner face of each arm is a wedge block 22 which projects through a slot 23 into the rectangular bore of the body. In 50 said bore is a rectangular plunger 24 which is formed at its inner end to provide bevelled surfaces 25 which co-operate with the wedge blocks 22 as hereinafter explained.

The plunger is connected at its upper end 55 to the tubular bore rod 26, and is axially movable but not rotatable in the reamer-body, the axial movement being limited. On opposite sides the plunger is recessed as at 27 and a pair of square keys 28 fitted 60 through the body partly take in said recesses. Thus the limit of axial movement of the plunger is determined by the length of the recesses less the width of the keys, and the length of such movement is so fixed 65 that when the reamer-body is suspended on

the bore rod, it moves downwardly on the plunger 24 until the keys 28 contact with the upper shoulders of the recesses 27. When in this position the bevelled surfaces 25 of the plunger are in their highest position relatively to the wedge blocks 22 and the arms 16 are permitted to swing inwardly so that they are flush with the sides of the body as shown in Fig. 2. When however the reamer-body is supported by 70 the bit (as when the tool as a whole is in operation) the weight of or on the bore-rod 26 forces the plunger 24 downwardly in the reamer-body and the bevelled surfaces 75 25 on the plunger contact with the wedge 80 blocks 22 and force the arms outwardly to operative position as shown in Fig. 1. When in this position the cutting tools 21 operate to cut an annulus 29 about the annulus 10 previously cut by the tools 7, 7. 85 The major diameter of the annulus 29 is not less than the external diameter of the casing to be used; and as the contracted reamer head is to be capable of passing upwardly through the casing, it is obvious that the 90 radial movement of the swinging end of each arm must be not less than the thickness of said casing. As an additional means of limiting the axial movement of the arms 18 projections 18¹ are formed on the upper 95 side of the head of arms 18 and recesses 18² are provided in the underside of the reamer body 16, so that the faces of projections 18¹ contact with the sides of the recesses 18² when the arms 18 are expressed to the desired amount. 100

To avoid strain on the pivotal bolts 19, the slots in which the arms 18 are housed, terminate in shoulders 30 against which the top ends of the arms bear when they the 105 arms are in operative position—see Fig. 1. Similarly the cutting tools 6 and 7 of the bit bear against shoulders 32 formed in the bit-body.

For the application of water during the 110 boring operation, the plunger 24, nipples 15 and 4 and bit-body 1 are all axially bored, the bore in the bit-body communicating with four divergent discharge holes 31.

What we claim and desire to secure by 115 Letters Patent is:—

1. In a well-boring tool, the combination with a bit capable of passing through the casing to be used, of a following underreamer comprising a body also capable of passing through said casing and having a rectangular axial bore, a plunger slidably fitting in said bore and formed for attachment to the bore rod said plunger having oppositely disposed bevelled surfaces, stops 120 limiting the travel of said plunger relatively to the body, a pair of swinging arms disposed within longitudinal grooves on the surface of the body and pivoted at their 125 upper ends to said body, wedge blocks pro- 130

jecting inwardly from said arms through apertures in the wall of the body and co-operating with the bevelled surfaces on the plunger to radially express the swinging 5 ends of said arms when the plunger is moved inwardly in the body but permitting their retraction when said plunger is moved outwardly, and cutting tools on the swinging ends of said arms, the whole so constructed that when said arms are retracted the under-reamer will pass through said casing, and when radially expressed the cutting tools thereon operate to enlarge the hole previously formed by the bit, to a diameter not less than the external diameter 15 of the casing.

2. In a well-boring tool including a bit capable of passing through the casing to be used, and a following under-reamer, an 20 under-reamer comprising a body also capable of passing through said casing and formed at one end for attachment to said bit, a rectangular plunger slidably fitting in a rectangular bore in said body, said 25 plunger being formed at its outer end for attachment to the bore-rod and on its inner end with opposed bevelled surfaces, a pair of swinging arms in longitudinal grooves

on the sides of the body, said arms being pivoted to the body at their upper ends and normally lying within said grooves, a head 30 on the swinging end of each arm, cutters mounted in said head, wedge blocks on said arms projecting inwardly through apertures in the body to co-operate with the bevelled 35 surfaces on the plunger, a recess on each of two opposite sides of the plunger, and transverse keys in the body engaging said recesses, and limiting the outward movement of the plunger relatively to the body, 40 the whole so constructed and arranged that inward movement of the plunger in the body radially expresses the cutter carrying arms, and outward movement permits same to swing inwardly so that the reamer as a 45 whole may be withdrawn through the casing of the bore-hole, projections formed on the heads of the swinging arms to engage recesses in the said body for the purpose of limiting the outward movement of the 50 swinging arms.

Signed at Sydney, N. S. W., this twenty-fifth day of September, A. D. 1922.

RICHARD FORD JENKINS.
DAVID WALTER PRICE.
